UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed January 27, 1922. Serial No. 532,188.

To all whom it may concern:

Be it known that I, BURNHAM C. STICKNEY, a citizen of the United States, residing in Elizabeth, in the county of Union and 5 State of New Jersey, have invented certain new and useful Improvements in Type-writing Machines, of which the following is a specification.

This invention relates to means for facilitating the introduction of cards, particularly 10 stencil address cards, into a typewriting machine and effecting the line-feeding movements thereof.

A stencil card usually consists of a small 15 piece of stencil paper having a frame or border which consists of card-board, and this frame is usually of such material that it is not desired to bend the stencil card around the platen.

20 Another difficulty that has been experienced in handling these cards is that they are not easily controlled by the platen and the feeding devices co-operating therewith, so that the cards are liable to skew at the line- 25 feeding operations.

It has been proposed to place the card in a frame and to gear the frame to the platen, so as to effect positive line-feeding of the card, but this requires expensive and 30 bulky mechanism for which there is usually no room in a front-strike typewriting machine.

The object of the invention is to overcome 35 these and other difficulties, and to effect further improvements. Upon the ends of the short platen, which is usually employed for typing stencil cards, there are placed, according to the present invention, finely toothed bands or wheels whose diameter ex- 40

ceeds that of the platen, these toothed or 45 knurled wheels being directly engaged by the sides of the stencil card frame for controlling the movements of the latter. There is provision also for pressing the card against said teeth or knurls, so that the teeth may 50 make slight indentations in the card, and hence the same is positively fed by the platen, the latter being operated by the usual line-feeding or rotating devices. This provision, which is simple and inexpensive, has 55 the further advantage that it becomes feasible to thrust the card down far enough to permit typing on its top border, which is a desideratum.

There is no frame or rack or 55 other device to be thrust down along the

parts of the typewriting machine, but only the card, for which there is room because of its thinness. The device which presses the side borders of the card against the knurled feed wheels may be prolonged downwardly to guide the card into the available space beneath the platen without bending the card to an objectionable extent; and there may be provided a guiding apron for the clear side of the card, said apron being 60 fixed upon the platen carriage and extending down nearly as far as the card drops. Thus stenciling can be effected without making alteration in the mechanism of the typewriter; the stencil feeding devices being 65 preferably such that they can be made and attached to the usual platen frame. 70

Provision is further made for releasing the card at one or both ends from the control of the knurled feed bands on the platen, so 75 as to permit the card to be adjusted at either or both ends.

Preferably the card-pressing fingers are flared forwardly above the printing line, and co-operate with the knurled bands or wheels 80 to form a throat into which the card may be dropped as far as it will go, the card coming to rest in a level position in this throat. Thereupon, the card is gently pressed downwardly 85 while the platen is rotated backwardly by the usual hand wheel, thus forcing the card into the bite of the toothed wheels and pressing fingers, so that the card is thereafter caused to follow the rotative movements of the platen. The teeth may press into the 90 card only slightly, just enough to control it without objectionably marring the same.

Other features and advantages will hereinafter appear. 95

In the accompanying drawings,

Figure 1 is a front elevation of the paper carriage of an Underwood front-strike typewriting machine embodying the present improvements.

Figure 2 is a sectional side elevation of the same, showing a card that has been introduced and run downwardly by the backward revolution of the platen until the top border of the card is in position to be typed. This view illustrates how, by means of the present 100 invention, very limited room in an Underwood machine may be found sufficient for the lower portion of the card. 105

Figure 3 is a view similar to Figure 2, but showing the card as just having been 110

pressed down between the platen and the pressing fingers and the backward rotation of the platen just started.

Figure 4 illustrates the operation of one of the release keys, of which there may be two, one at each end of the platen, so that either end of the card may be released independently of the other for truing up the card.

10 Figure 5 illustrates the preferred method of bringing the card to a level or true position at the introduction of the same.

15 Figure 6 is a perspective sectional view of a pressing finger, etc., at one end of the platen.

Figure 7 is an enlarged fragmentary side elevation illustrating co-operation of the pressing finger and the toothed wheel relatively to the card and platen.

20 Figure 8 is a view similar to Figure 5, but showing another form of tooth on the wheel.

A short cylindrical platen 10, which may have a celluloid surface (not shown) is journaled by means of an axle 11 in ends 12, 13 of an Underwood platen frame, which also comprises a connecting bar 14; said axle having finger-wheels or handles 15 and also a ratchet or line-space wheel 16, in which runs a detent roll 17 mounted upon a spring-pressed arm 18 forming part of the line-spacing mechanism. The latter mechanism also includes a handle 19, which returns the platen frame and carriage to the beginning of a new line, said handle usually having an arm 21 to press back a slide 22 and thereby operate the usual pawl (not shown), which engages the ratchet-wheel 16.

It is customary to use the short platen 10 for stencil cards for writing purposes, and this style of platen is shown for convenience of illustration; and upon the ends of the platen are provided bands or wheels 23 having relatively fine teeth 24 which protrude slightly from the platen, as seen best at Figure 7, for the purpose of pressing into or penetrating the unbroken surfaces of the side borders 25 of a stencil card 25^a, whose top border is indicated at 26 and bottom border at 27, the borders forming the usual rectangular frame. The extent to which the teeth penetrate the card is exaggerated in the views, which are diagrammatic; but it will be understood that there may be only enough denting of the card to give the platen a reliable control of the same. The card is pressed against the teeth by means of spring fingers 28, which may press the card upon the teeth until the card touches the periphery of the platen, Figure 7. These fingers 28 are pivoted at 29 upon ears 30 formed upon pendent brackets 31 near the ends of the platen. These brackets 31 may be fixed upon a cross-bar 32 extending from end to end of the platen frame, and provided at its

ends with arms 33, whereby it is secured by the use of screws 34 to the tops of the ends 12, 13 of said platen frame; said screws 34 being usually employed in said machine for securing attachments to said platen frame. 70

It will be seen that the card-guiding devices may form a unit, all parts thereof supported upon said cross-bar 32 for facility in manufacturing and shipping and attachment to the machine. Upon the brackets 31 may be secured springs 35 to press the fingers 28 against the card; these springs bearing against arms 36 from which may rise vertical arms 37 having finger-pieces 38 to press the fingers 28 upon the pivots 29 away from the platen to release the card at either or both ends, as at Figure 4. These finger-pieces 38 may be extended to each other and approach each other so closely as to be operable by the fingers of one hand, so as to enable both pressing fingers to be released simultaneously if desired.

The arms 36 are connected to the fingers 28 by means of upwardly-flaring finger extensions 39, which co-operate with the knurls 24 to form introductory throats for the card, as at Figures 5 and 8, there being such a substantial angle between the peripheral line of the teeth and the forwardly and upwardly inclined member 39 of the throat that the members where they meet may constitute a gage down against which the card may be set, so that the card will be leveled by reason of its contact with the bottoms of the throats, so that it is only necessary to press the card down into the machine as far as it will go and then rotate one of the handles 15 backwardly and maintain the downward pressure on the card, which forces the card into the bite of the teeth and the pressing fingers 28, Figure 3, said teeth and fingers thereafter controlling the movements of the card. If desired, the teeth may be of a coarse pitch, and the lower edge of the card may be gaged by 105 said teeth, as at Figure 5, the teeth on one wheel 23 being in alignment with those on the other wheel, the teeth on one wheel being the same as those on the other, and being in multiple of the number of teeth on the ratchet-wheel 16, so that a tooth on each wheel is always correctly positioned at the junction of each throat plate 39 and the co-operating wheel 23.

As the card is thrust down towards the Figure 2 position, it may be guided by front and rear guides forming a throat, the front guides 40 being in the nature of downward and rearward slightly curved extensions of the guide fingers 28, and the rear guide being in the nature of a plate or apron 41 extending across under the platen, and inclined downwardly and rearwardly in such relation to the front guides 40 as to guide the card as it slides down past said guides 130

and prevent the card from fouling upon the cross-rods 42, 43 usually provided in the platen frame. This guide plate 41 may have ears 44 whereby it may be attached

5 to the lower ends of extensions 45 formed upon the brackets 31. The plate 41, together with the brackets 31 and cross-bar 32, makes a substantial frame to carry all of the remaining parts of the card-guiding 10 device.

Variations may be resorted to within the scope of the invention, and portions of the improvements may be used without others.

Having thus described my invention,

15 I claim:

1. In a front-strike typewriting machine, the combination with typing instrumentalities and a platen, of means for embossing a complete set of toothed indentations upon 20 a stencil-card upon inserting the card downwardly bottom end foremost in the machine at the printing line preparatory to employing said set to line-feed the card, said embossing means including backwardly rev- 25 oluble circumferential rows of teeth associated with the ends of said platen, and lips at the front of the teeth and platen and diverging therefrom outwardly at about the printing line, and having downwardly- 30 directed extensions forcing the card against said teeth, during its downward movement, causing the teeth to sink into the card, embossing indentations therein, said extensions also holding the card to the platen and to 35 the teeth for the subsequent typing and line-feeding operations, and continued down to form card-guides extending below the platen, the rows of teeth being rotatable step by step by 40 means of the engagement of said rows of teeth with said embossed indentations, said extensions being releasable to permit adjustment and trueing of the card, and a plate extending under the platen in rear of said extensions, and co-operating therewith to form a chute or guide for the card.

2. In a front-strike typewriting machine, 45 the combination with typing instrumentalities, of a combined introducer and feeder for stencil-cards inserted downwardly bottom end foremost in the machine at the printing line, comprising a backwardly rev-

50 oluble platen having circumferential rows of teeth and forming one element of the introducer and feeder, said introducer and feeder also comprising lips at the front of the platen and diverging therefrom outwardly at about the printing line, and having downwardly-directed extensions pressing a card against 55 said teeth and causing them to partially penetrate the card, said extensions holding the card to the platen for the typing operation, and continued down to form card-guides extending below the platen, the platen being rotatable in line-feeding direction and feeding the introduced card up again line by line by means of the engagement of said teeth with said indentations in the card during the back or down stroke of the platen and card, said extensions being movable to 60 permit adjustment and trueing of the card, and a plate extending under the platen in rear of said extensions, and co-operating therewith to form a chute or guide for the card, said chute open at its bottom, so that

embossed in the card during the back or down stroke of the platen and card, said extensions being releasable to permit adjustment and trueing of the card.

3. In a front-strike typewriting machine, 70 the combination with typing instrumentalities and a platen, of means for embossing a complete set of toothed indentations upon a stencil-card upon inserting the card downwardly bottom end foremost in the machine 75 at the printing line preparatory to employing said set to line-feed the card, said embossing means including backwardly revoluble circumferential rows of teeth associated with the ends of said platen, and lips at the 80 front of the teeth and platen and diverging therefrom outwardly at about the printing line, and having downwardly-directed extensions forcing the card against said teeth during its downward movement, causing 85 the teeth to sink into the card, embossing indentations therein, said extensions also holding the card to the platen and to the teeth for the subsequent typing and line-feeding operations, and continued down to 90 form card-guides extending below the platen, the rows of teeth being rotatable step by step in line-feeding direction and accurately feeding the introduced card up again line by line by means of the engagement of said 95 rows of teeth with said embossed indentations, said extensions being releasable to permit adjustment and trueing of the card, and a plate extending under the platen in rear of said extensions, and co-operating therewith to form a chute or guide for the card.

4. In a front-strike typewriting machine, 100 the combination with typing instrumentalities of a combined introducer and feeder for stencil-cards inserted downwardly bottom end foremost in the machine at the printing line, comprising a backwardly revoluble platen having circumferential rows of teeth and forming one element of the introducer and feeder, said introducer and feeder also comprising lips at the front of the platen and diverging therefrom outwardly at about the printing line, and having downwardly-directed extensions pressing a card against 105 said teeth and causing them to partially penetrate the card, said extensions holding the card to the platen for the typing operation, and continued down to form card-guides extending below the platen, the platen being rotatable in line-feeding direction and feeding the introduced card up again line by line by means of the engagement of said teeth with said indentations in the card during the back or down stroke of the platen and card, said extensions being movable to 110 permit adjustment and trueing of the card, and a plate extending under the platen in rear of said extensions, and co-operating therewith to form a chute or guide for the card, said chute open at its bottom, so that

115

120

125

130

the card may descend beyond the same, and formed to direct the card clear of the typewriter mechanism below the chute.

5. In a front-strike typewriting machine, the combination with typing instrumentalities and a platen, of means for embossing a complete set of toothed indentations upon a stencil-card upon inserting the card downwardly bottom end foremost in the machine at the printing line, preparatory to employing said set to line-feed the card, said embossing means including backwardly revolvable circumferential rows of teeth associated with the ends of said platen, and lips at the front of the teeth and platen and diverging therefrom outwardly at about the printing line, and having downwardly-directed extensions forcing the card against said teeth, during its downward movement, causing the teeth to sink into the card, embossing indentations therein, said extensions also holding the card to the platen and to the teeth for the subsequent typing and line-feeding operations, and continued down to form card-guides extending below the platen, the rows of teeth being rotatable step by step in line-feeding direction and accurately feeding the introduced card up again line by line by means of the engagement of said rows of teeth with said embossed indentations, said lips directed upwardly and forwardly from said rows of teeth and supporting the card as it is presented to the machine, and co-operatively with said teeth forming a leveling gage for the bottom edge of the card being introduced.

6. The combination of a carriage comprising two end plates, a platen supported on said carriage, a revolute shaft supported in said end plates, toothed driving elements secured to said shaft, a cross-bar secured to said end plates, brackets fixed on said cross-bar, pressure-fingers pivoted on said brackets, and springs for said fingers to press a card against the driving elements with sufficient pressure to indent the card so that the card may be fed about the platen by revolving said shaft.

7. The combination of a carriage, a revolute platen on said carriage, a type-bar segment, movable curved guide-fingers arranged to travel with said carriage to direct a card downwardly from the front of said platen behind the type-bar segment, the upper ends of said guide-fingers having bent-off portions flaring outwardly to form receptacles with the platen for the card, two driving devices at the ends of said platen having teeth to partially penetrate the unbroken surface of the card to feed the latter about the platen, and a guide-bar to keep the bottom edge of the card from colliding with devices behind the type-bar segment.

8. The combination of a platen, a frame to support said platen, said frame comprising

two end plates, a revolute shaft in said frame, two driving devices on said shaft to feed a card about the platen, a cross-bar secured to the end plates, brackets on said cross-bar, spring-pressed fingers pivoted on said brackets to guide said card and hold it against the driving devices, and a guide-bar secured to the lower end of said brackets to assist in guiding the card.

9. A detachable bracket or platen-frame for a rotating platen typewriter, said bracket having pressure-fingers to press a card against toothed wheels provided upon the ends of the platen, and also having means to release said pressure-fingers, said fingers having downward extensions, and said bracket having an apron below the platen to co-operate with said downward extensions to guide the card downwardly, whereby typing may be done upon the top margin of the card.

10. The combination with a platen, a line-space wheel therefor and a detent for the line-space wheel, of toothed wheels at the ends of the platen, and means at the ends of the platen to form an introductory guide for the lower edge of a card, said introductory means so placed with reference to the toothed wheels that the lower edge of the card may rest upon teeth of the wheels, whereby said teeth may serve as leveling gages for the card, said teeth having an aliquot relation to the teeth of the line-space wheel, so that the card-gaging position of the toothed platen-wheels may be always the same.

11. In combination, a platen, a supporting shaft having line-spacing means for driving the shaft, card feeding means on said shaft having teeth to partially penetrate and to feed a card about the platen, guide fingers pivoted for operation independently of each other, each finger being spring-pressed and adapted to hold said card in contact with the platen, finger pieces above the pivots which when pressed together remove separately said guide fingers from said feeding devices to enable the ends of the cards to be adjusted relatively to each other and the platen.

12. In combination, a shaft, a platen thereon, line-spacing mechanism to rotate said shaft, toothed devices on said shaft to feed a card about the platen, and guide fingers separately operable to hold said card in contact with the feeding devices, each guide finger having a handle extending toward the other finger whereby the handles may both be engaged by one hand of the typist and both guide fingers or either guide finger released from pressure against the card.

13. The combination of a shaft, a platen thereon, line-spacing mechanism to rotate said shaft, driving devices on said shaft

to feed a card about the platen, pivoted guide fingers separately operable to hold said card in contact with the driving devices, springs separately operable to press said guide fingers toward said driving devices, and individual handles by which said guide fingers may be separately released against the tension of said fingers for adjusting the card.

10 14. In a front-strike typewriting machine, the combination with a platen, of means for moving an imperforate stencil-card in

straight condition downwardly in front of the platen to typing position and line-feeding it upwardly without liability of skewing, including circumferential sets of card-indenting teeth at the ends of the platen, and means in front of the platen pressing the card against the teeth and co-operative therewith to maintain the card positively in level condition throughout its downward and upward movements.

BURNHAM C. STICKNEY.
